UNITED STATES PATENT OFFICE.

ARCHIBALD F. REDDIE, OF PHILADELPHIA, PENNSYLVANIA, ASSIGNOR TO
MC CALLUM & MC CALLUM, OF SAME PLACE.

DESIGN FOR CARPET.

SPECIFICATION forming part of Design No. 25,297, dated March 24, 1896.

Application filed February 24, 1896. Serial No. 580,530. Term of patent 3½ years.

To all whom it may concern:

Be it known that I, ARCHIBALD F. REDDIE, a citizen of the United States, residing at the city of Philadelphia, in the county of Philadelphia and State of Pennsylvania, have invented and produced a new and original Design 5 for a Carpet or other Fabric, of which the following, taken in connection with the accompanying drawing, is a specification.

- 10 o The design of my invention comprises a pattern or ornamentation which may be applied to or wrought upon Brussels, Wilton, velvet or other carpeting in such colors and combinations of colors or tints as may be desired; and I do hereby declare that the drawing accompanying this specification presents to the eye of the observer a clear comprehension of the pattern or ornamentation which constitutes my new and original design in 15 such manner that it may be readily distinguished from all other designs.

In said drawing, A is the body, B the border, and A and B the carpet.

To assist others in ascertaining the characteristic feature of my design, I would direct 25 attention to the leading features of the pattern illustrated in the drawing which may be said to be the corniform figures *a* and *b*, displayed upon a background *c*.

What I claim as new, and desire to secure 30 by Letters Patent, is—

- 1. In the design for the carpet the body A, substantially as shown.
- 2. In a design for a carpet the border B, substantially as shown. 35
- 3. The design for a carpet consisting of the body A, and the border B, substantially as shown.

In testimony whereof I have hereunto signed my name in the presence of two witnesses. 40

ARCHIBALD F. REDDIE.
